DESIGN FOR A SCREW DRIVER

Rudolph J. Velepec, Rochester, N. Y., assignor to
Upson Brothers, Inc., Rochester, N. Y., a corporation of New York

Application March 30, 1938, Serial No. 76,197

Term of patent 14 years

To all whom it may concern:

Be it known that I, Rudolph J. Velepec, a citizen of the United States, residing at Rochester, in the county of Monroe and State of New York, have invented a new, original, and ornamental Design for Screw Drivers, of which the following is a specification, reference being had to the accompanying drawing, forming part thereof.

In the drawing:

Figure 1 is a perspective view of a screw driver showing my new design.

Figures 2 and 3 are respectively longitudinal and transverse sectional views on the lines 2—2 and 3—3 of Figure 1.

I claim:

The ornamental design for a screw driver, as shown.

RUDOLPH J. VELEPEC.
